United States Patent Office.

H. STICKNEY, OF CLEVELAND, OHIO.

Letters Patent No. 95,949, dated October 19, 1869.

COAL-STOVE.

The Schedule referred to in these Letters Patent and making part of the same.

To all whom it may concern:

Be it known that I, H. STICKNEY, of Cleveland, in the county of Cuyahoga, and State of Ohio, have invented a new and improved Heater; and I do hereby declare that the following is a full, clear, and exact description thereof, which will enable others skilled in the art to make and use the same, reference being had to the accompanying drawings, forming part of this specification.

This invention relates to improvements in base-burning heaters, having for its object to provide certain improvements in the construction and arrangement of the base, and in the application of water-vessels around the same;

Also, an improved radiating apparatus;

Also, an improved valve-arrangement in the magazine, for preventing the escape of the gas therefrom, and for admitting the supply of coal;

Also, an improved means for operating the grate to discharge the ash and cinder; and

Also, an arrangement for closing the draught-door, by the action of the feed-door in opening, to prevent the escape of gas, when supplying the magazine.

Figure 1 represents a sectional elevation of my improved heater;

Figure 2 represents a plan of the grate and the base; and

Figure 3 represents a detail, showing a modified arrangement of self-acting valve, adapted for vertical magazines.

Similar letters of reference indicate corresponding parts.

The base A, surrounding the ash-pit B, is made large and conical, furnishing a rest on the inclined sides thereof, for the water-vessels C.

This water-vessel surrounds the enclosure containing the fire, and prevents the same from burning out by the intense heat to which it is subjected, absorbing and transmitting the heat therefrom as it radiates in that direction.

D represents the grate, which is fixed, and provided with a central opening, E, and radial openings F, and above it a stirrer, G, is placed, which is made to oscillate over the plate D and the openings therein, by a crank, H, below, connected to the central stem of the stirrer and a connecting-rod, I, which is provided with an eye, K, at the outer end, through which a lever or poker, L, may be placed, and engaged with a holder at the bottom, so as to have greater leverage in working the stirrer.

Above the fire-pot M, I arrange a radiating-drum, N, through which the products of combustion pass.

The walls of this drum resemble in form a series

of sections of cones, superposed upon each other, the cones of the outer wall being inverted.

This arrangement provides a great amount of heating-surface. Any number of conical sections may be used, and the drum extended vertically, more or less, as required.

The magazine is designed to be made with a joint at Q, for the introduction of extension-pipe, to lengthen it with the drums when required.

R represents a self-closing valve, placed in the magazine, to prevent the escape of gas, and so arranged as to be opened by the coal when poured in.

In fig. 3, R' represents another self-closing arrangement of magazine-valves, such as I design to use when the magazine rises vertically to the top. In this case the valve is hinged to a plate, S, projecting from one side, closing a part of the passage, and protecting the weighted arm T from the coal.

I propose to attach a connecting-rod, U, to the draught-door V, below, arranged to suspend the said door from the catch W, of the magazine-door X, so that when the latter is opened it will disconnect the suspending rod, and allow the draught-door V to close while the magazine is being supplied, whereby an inward draught will be induced at the magazine-door, and the gas thereby prevented from escaping while supplying fresh coal.

Having thus described my invention,

I claim as new, and desire to secure by Letters Patent—

1. The arrangement, in a heater and about the magazine, of the radiator N, surrounding the reservoir P, and formed of two conical frusta, but having the respective bases thereof reversed, all as shown and described.

2. The combination of a fire-pot, M, and stirrer G, with a magazine, P, having a self-adjusting valve, all operating together, to supply, contain, and stir the fuel, as set forth.

3. The combination, with the grate-lever H, of the rod I, and operating lever L, when arranged substantially as specified.

4. The combination of the draught-door V, magazine-door X, catch W, and connecting-rod U, when arranged for causing the draught-door to be disconnected from the suspending catch, for closing the same by the action of the magazine-door, when opened, all substantially as specified.

H. STICKNEY.
